AIR COOLED INTERNAL COMBUSTION ENGINE

Leo J. Lechtenberg, Elm Grove, Robert K. Catterson, Brookfield, and Joseph V. Reichenbach, Milwaukee, Wis., assignors to Briggs & Stratton Corporation, Milwaukee, Wis., a corporation of Delaware
Original application June 27, 1962, Ser. No. 205,658, now Patent No. 3,118,433, dated Jan. 21, 1964. Divided and this application Oct. 3, 1963, Ser. No. 313,546
5 Claims. (Cl. 123—119)

This invention, like that of the application of Leo J. Lechtenberg, Serial No. 205,658, now Patent No. 3,118,433, of which this is a division, relates to internal combustion engines and refers more particularly to single cylinder air-cooled engines of the type widely used on power lawn mowers.

The object of this invention is to provide a simplified and more practical carburetor for engines of the type indicated, particularly from the standpoint of assuring continued freedom of adjustment of its throttle valve and choke valve, even in dusty and sandy surroundings.

With the above and other objects in view which will appear as the description proceeds, this invention resides in the novel construction, combination and arrangement of parts substantially as hereinafter described and more particularly defined by the appended claims, it being understood that such changes in the precise embodiment of the herein disclosed invention may be made as come within the scope of the claims.

The accompanying drawings illustrate one complete example of the physical embodiment of the invention, constructed according to the best mode so far devised for the practical application of the principles thereof, and in which:

FIGURE 1 is a vertical sectional view through an engine equipped with the carburetor of this invention;

FIGURE 2 is a separated perspective view of the carburetor, a portion of the fuel tank on which it is mounted, and the air cleaner;

FIGURE 3 is a perspective view of the assembled carburetor, but with the air cleaner omitted;

FIGURE 4 is a fragmentary perspective view illustrating a detail of the ignition grounding switch of the engine, with the various parts shown separated from one another; and

FIGURE 5 is a top view of the carburetor and adjacent structure, but with the air cleaner removed.

Referring now particularly to the accompanying drawings, the numeral 5 indicates generally the main body of the engine which preferably is a die casting such as that of the Lechtenberg Patent No. 2,693,789. Hence, the main body casting forms all but one of the walls of the crankcase and also the finned cylinder 6. The open side of the crankcase, in the vertical shaft engine shown in FIGURE 1, is closed by a cover casting 7 which has the mounting flange 8 of the engine formed thereon and which also provides an oil sump for the crankcase and contains the lower crankshaft bearing (not shown). This lower bearing and another upper bearing also not shown, in the top wall of the crankcase, rotatably mount the crankshaft 9 of the engine, one end portion of which projects downwardly beyond the mounting flange to have the cutter blade of a mower or other instrumentality to be driven secured thereto.

The outer end of the cylinder 6 is, of course, closed by a cylinder head (not shown) which is secured in place by bolts or capscrews 10. As is customary, both the cylinder and the cylinder head have heat dissipating fins thereon.

The upper end of the crankshaft has a flywheel 11 fixed thereto which also serves as the rotor of the engine magneto, indicated generally by the numeral 12. Air

2

propelling blades 13 on the upper face of the flywheel provide an air impeller or blower capable of delivering a substantial flow of cooling air for the engine. Duct means indicated generally by the numeral 14 directs the cooling air transversely across the finned cylinder 6 and cylinder head.

A rewind-type rope starter indicated generally by the numeral 15 is mounted on the shroud and connected in the customary manner with the upper end of the crankshaft to provide means for starting the engine.

The engine is of the L-head type and, hence, has intake and exhaust ports 16 and 17 in its cylinder casting. These ports are spaced apart lengthwise of the crankshaft axis with the intake port 16 nearest the air impeller or blower. As is customary, the ports open to valve seats 18 and 19 in the top or outer face of the cylinder casting, and with which the intake valves 20 and 21 coat in the customary manner.

It is significant to note that the intake port 16 opens 20 toward that side of the cylinder which faces the impeller or blower, i.e. upwardly in the case of the vertical shaft engine shown in FIGURE 1; and that the exhaust port 17 opens laterally or horizontally away from the cylinder.

A muffler 22 is bolted to the cylinder casting over the 25 mouth of the exhaust port 17. This muffler is of novel construction and forms the subject matter of a copending application, Serial No. 233,005, filed October 25, 1962.

At the side of the cylinder opposite that at which the intake and exhaust ports are located, is a fuel tank 23 and 30 the improved carburetor of this invention, indicated generally by the numeral 24. The fuel tank 23 has a generally oblong or rectangular shape and is mounted directly alongside the cylinder crankcase casting with its top wall 25 substantially in line with the upper side of the cylinder—or, more specifically, the cooling fins on the cylinder, as clearly seen in FIGURE 1.

The tank 23 is secured in position by means of suitable mounting brackets, spot welded to the opposite ends of the tank, and bolted to the crankcase cylinder casting.

40 Since the mounting brackets are spot welded to the opposite ends of the fuel tank, the points of securement of the tank to the engine are relatively widely spaced, and being as firmly anchored as they are, it follows that there is no likelihood whatsoever that the fuel tank will work 45 loose as a result of engine vibration. Also, since the carburetor 24 is mounted upon the top wall 25 of the fuel tank by means of a relatively large flange 26, the bottom face of which seats squarely upon the top wall 25 of the tank, utmost assurance is had against loosening of the carburetor. The flange 26 may be secured 50 to the top wall of the tank in any suitable way, as by cap screws 27.

The carburetor is of the type disclosed in the Brown et al. Patent No. 2,529,242. Hence, it has a die cast 55 tubular body 28 which provides a mixture passage 29 in which the fuel and air is admixed and from which the fuel-air mixture issues for delivery to the intake port, and has the flange 26 formed integrally therewith. The fuel is drawn into the mixture passage 29 by engine suction through a suction tube 30 which projects perpendicularly from the bottom of the carburetor mounting flange 26 into a cup or reservoir 31 in the upper portion 60 of the fuel tank. The fuel delivered by the suction tube 30 enters the mixture passage of the carburetor through jets (not shown) under the control of a needle valve 32 in the customary manner.

The cup or reservoir is kept filled with fuel from the fuel tank by an engine-suction actuated diaphragm pump 65 33, which is mounted on the side of a carburetor body opposite its needle valve, and the inlet of which has a suction feed tube 34 connected thereto to project down

into the fuel tank with its suction mouth located near the bottom of the tank.

Air enters the carburetor through an air cleaner 35 which preferably is of the type disclosed in Patent No. 2,999,562, and which is seated upon an upwardly facing flange 36 encircling the mouth of an air inlet port 37, being removably held in place by a screw 38 which extends axially down into the air inlet port and is threaded into the bottom wall of the carburetor body.

The air cleaner 35 not only serves to clean the air fed to the carburetor, but also provides filtered communication between the atmosphere and a crankcase breather 39 which is preferably of the type shown in Patent No. 2,693,791, and hence is located on the side of the crankcase adjacent to the intake and exhaust ports. A tube 40 connects the crankcase breather with the air intake port of the carburetor, for which purpose the carburetor body has a tubular projection 41 at one side thereof connectible with the tube.

The discharge end portion 42 of the mixture passage of the carburetor is connected with the intake port 16 by a tube 43 which extends transversely across the upwardly facing side of the cylinder. One end of the tube 43 telescopes into the discharge end portion 42 of the mixture passage and its opposite end is received in a die cast elbow 44 which is bolted to the top face of the crankcase cylinder casting over the mouth of the intake port 16.

The choke valve 45 of the carburetor and its mounting are rather unique. Both the choke valve and its mounting shaft 46 are molded of plastic such as Delrin. The valve 45 is a generally circular disc having a hole 47 at its center of a size to permit the screw 38 which holds the air cleaner in place to pass therethrough. To enable the disc to be rotated by its mounting shaft 46 through 90° the disc is formed with oppositely facing semicylindrical grooves 48 which embrace the screw 38 when the choke valve is in its full open position, and the inner ends 49 of these grooves, which actually provide the edges of the hole 47, are disposed at an angle of substantially 45° to the plane of the disc, to abut the sides of the screw when the disc is in its fully closed position. Accordingly, the screw passing through the choke valve disc serves to define the angle through which the choke valve may be turned.

The mounting shaft 46 of the choke valve is journaled in a bore 50 extending radially through the cylindrical wall which defines the air inlet port 37 and has a bifurcated inner end portion 51 projecting into the air inlet port to embrace the adjacent portion 52 of the choke valve disc. The slot defined by the bifurcations of the shaft is just wide enough to snugly receive the disc portion 52, and parallel ridges 53 on the opposite faces of the disc engage the edges of the slot to hold the disc against lateral edgewise displacement with respect to the mounting shaft.

Endwise separation of the shaft and disc is normally prevented by a detent consisting of a pair of ridges 54 on the opposite faces of this disc and transverse grooves 55 in the sides of the slot defined by the bifurcations of the shaft. To effect assembly of the choke valve and its shaft it is only necessary to insert the valve disc into the air inlet port, align its portion 52 with the bore 50 and insert the shaft 46, whereupon the inner bifurcated end portion of the shaft is slid onto the disc far enough to engage the detent between the shaft and the disc.

A torsion spring 56 on the outer projecting end portion of the shaft 46 biases the choke valve to its open position. One end of this spring is hooked onto a portion of the carburetor body and its other end engages a lug 57 projecting from the shaft. An arm 58 also projecting from the outer end portion of the shaft—and preferably disposed at a right angle to the lug 57—provides means by which the shaft may be rotated to close the choke valve. This is done by a control lever

59 which is pivoted, as at 60, to the top face of a mounting plate 61 which, in turn, is attached to the carburetor body preferably by means of screws 62 passing through downwardly projecting flanges on the mounting plate and screwed into bosses on the side of the carburetor body. The mounting plate 61 is thus firmly attached to the carburetor.

10 The control lever 59 has an arm 63 which swings in an arcuate path so disposed with respect to the location of the arm 58 on the outer end of the choke valve as to collide therewith as the control lever is moved in a clockwise direction, as viewed in FIGURE 5 beyond its full line position there shown.

15 Another arm 64 on the control lever 59 is connected through a spring 65 with a lever 66 connected in the customary manner with a mechanical governor, not shown, it being understood that the lever 66 is moved back and forth by the governor and that such motion thereof is transmitted to the throttle valve of the carburetor (not shown) through a link 67 which connects with an arm 68 fixed to the throttle valve shaft. The arm 68 has a portion thereof located to collide with a fixed abutment 69 to thereby define the full open position of the throttle valve, and carries a screw 70 which engages the other side of the abutment 69 to define the closed position of the throttle valve, the adjustability of the screw 70 affording an idling adjustment for the engine.

20 The control lever 59 also provides the means for closing an ignition shorting switch, indicated generally by the numeral 71. The manner in which this switch is constructed and mounted on the plate 61 is rather novel. As shown, the ignition grounding switch 71 comprises a bifurcated spring metal stamping, having a short arm 72 and a longer arm 73. This stamping is carried by an insulated mounting pad 74 to which it is secured by having its rear edge portion 75, which is curved downwardly, engaged with a ledge 76 on the underside of the mounting pad, in coaction with a novel connection between the short arm 72 of the stamping and a small boss 77 on the underside of the mounting pad. This boss projects through a hole 78 in the short arm 72 and a tongue 79 snaps over a ledge 80 on the boss. With the stamping thus attached to the pad 74, its long arm 73 lies flat against the underside of the pad with a finger 81 on its extremity projecting through a hole 82 in the mounting plate to be engaged by a portion of the control lever 59 when the latter is moved to its "Stop" position, the resilience of the stamping permitting the arm 73 to flex as the grounding connection is made.

25 The short arm 72 is sprung downwardly away from the pad and slightly beyond a hole 83 in the boss 77. This provides a convenient way of connecting a wire lead 84 with the metal stamping. To do so, the short arm 72 is pressed upwardly beyond the hole to allow the bared end of the wire to be inserted into the hole beneath the arm 72, which upon being released makes secure contact with the wire.

30 The insulated mounting pad 74 is attached to the plate 61 in its proper position by means of a pair of upwardly directed spaced fingers 85-86 on the pad which embrace the portion of the mounting plate lying between a slot 87 therein and its adjacent edge. Ridges 88 on the outer ends of these fingers snap over the edges of the embraced portion 87.

35 Preferably a stop 89 projects up from the mounting plate 61 into the path of the control lever 59 to provide a positive limit for the motion of the control lever toward its full choke position so as to preclude damage to the choke valve; and coacting detents on the lever and the mounting plate define the "Start," "Running" and "Stop" positions of the control lever.

40 The mounting plate 61 has still another function. When mounted on the carburetor it precludes separation of the shaft 46 from the choke valve disc. For this pur-

pose, a lug 90 projects from the mounting plate in line with the outer end of the shaft.

What is claimed as our invention is:

1. In a carburetor having a tubular body providing a mixture passage in which fuel and air are admixed, an air inlet port leading to said passage and defined by a cylindrical wall, and a choke valve to control the admission of air into the mixture passage through the air inlet port, the improvement which resides in the following features:

(A) the choke valve is of the butterfly type and comprises a disc of a size to substantially close the air inlet port

(B) and the mounting for the choke valve comprises (1) a radial bore through one side of the cylindrical wall of the air inlet port

(2) a shaft journaled in said bore having a bifurcated inner end portion projecting into the air inlet port and slidably embracing the adjacent part of the disc,

(3) interengaging guide means on the disc and the bifurcated end portion of the shaft parallel with the shaft axis to hold the disc against the lateral edgewise displacement from the shaft, and

(4) interengaging detent means on the disc of the shaft to firmly though detachably hold the disc and shaft assembled.

2. The carburetor of claim 1, further characterized by the following additional features:

(A) the disc and its mounting shaft are plastic moldings, and

(B) the carburetor body is formed of metal so that the likelihood of having the shaft become "frozen" in the bore is minimized.

3. The carburetor of claim 2, further characterized by the following additional features:

(A) means to define the open and closed positions of the choke valve;

(B) a torsion spring encircling the outer end portion of the shaft and having one end connected to the carburetor body and its other end connected to the shaft to yieldingly bias the shaft in the direction to hold the choke valve open, and

(C) means on the outer end portion of the shaft by which the shaft may be turned to close the choke valve.

4. The carburetor of claim 3, further characterized by the following additional features:

(A) an air cleaner to filter the air which enters the air inlet port,

(B) and a screw to hold the air cleaner in place over the mouth of the air inlet port,

(1) said screw extending into the air inlet port

and passing through a hole in the center of the choke valve, and being threaded into the carburetor body, and

(C) the choke valve having oppositely facing radial grooves in its opposite faces to receive the screw and thus allow the choke valve to assume its open position substantially parallel with the axis of the screw.

5. In a control for an internal combustion engine having an ignition system and a carburetor having a tubular body defining a mixture passage with an air inlet port, a throttle valve in the mixture passage and a choke valve to control the admission of air into the mixture passage from the air inlet port, the improvement which comprises:

(A) a shaft journaled in a bore in one side of the carburetor body having its inner end connected to the choke valve to mount and adjust the same as the shaft is turned,

(1) the outer end portion of the shaft having an arm projecting radially therefrom to provide means by which the shaft may be turned;

(B) a spring reacting between the shaft and the carburetor body biasing the same in one direction of rotation to thereby yieldingly urge the choke valve toward its open position;

(C) a mounting plate fixed to the carburetor body at the side thereof at which said shaft is located and with the plane of the mounting plate substantially parallel to the axis of the shaft;

(D) a control lever pivoted to said plate to swing about a fixed axis perpendicular to the plate;

(E) an abutment on the control lever to collide with said arm which projects from the shaft, and thereby turn the shaft in opposition to the spring bias thereon as the lever is swung about its pivotal mounting in one direction beyond a predetermined position;

(F) means providing a connection between the control lever and the throttle valve through which adjustment of the lever effects adjustment of the throttle valve; and

(G) an ignition grounding switch carried by the mounting plate with a portion thereof projecting through a hole in the plate into the path of a portion of the control lever to be engaged thereby and thereby effect grounding of the ignition system upon movement of the control lever to a predetermined position at which the choke valve is open and the throttle valve closed.
